UNITED STATES PATENT OFFICE

BLANCHARD D. SMITH, OF NEW ORLEANS, LOUISIANA, ASSIGNOR TO B. D. SMITH, INC., OF NEW ORLEANS, LOUISIANA, A CORPORATION

GOLF DRIVING DEVICE

Application filed August 23, 1930. Serial No. 477,372.

My invention relates to improvements in apparatus for playing or practicing games such as golf.

An important object of my invention is 5 the provision of an apparatus which simulates the conditions existing on a real golf course, although requiring only a relatively small space.

Another object of my invention is to provide a device for calculating the distance that 10 a ball, struck by the player, would have traveled on a golf course.

A further object of my invention is the provision of means for determining the initial 15 velocity of the ball when struck.

Yet another object of my invention is to consider the direction of the ball's flight in calculating the distance of the flight.

Other objects and advantages of my invention 20 will be apparent during the course of the following description.

In the accompanying drawings, which 25 form a part of this specification, and wherein like characters of reference denote like or corresponding parts throughout the same,

Figure 1 is a longitudinal sectional view of my improved driving apparatus,

Figure 2 is a plan view thereof,

Figure 3 is a front elevation,

Figure 4 is a plan view of the driving tee,

Figure 5 is a longitudinal sectional view

thereof,

Figure 6 is a detail view of one of the tees,

Figure 7 is an enlarged detail view thereof,

Figure 8 is a detail of the tee contacts and insulating strip,

Figure 9 is a front elevation of the drive 40 indicator,

Figure 10 is a rear elevation thereof,

Figure 11 is a vertical sectional view there- 45 through,

Figure 12 is a detail of the mat contact mechanism,

Figure 13 is a detail view of the indicator release mechanism,

Figure 14 is a detail view showing the tee 50 making contact between the contact strips,

Figure 15 is a detail view of the indicator

brake mechanism, parts being broken away, and

Figure 16 is a fragmentary plan view thereof, parts being removed.

In the drawings, wherein for the purpose 55 of illustration is shown a preferred embodiment of my invention, the numeral 17 designates an elongated cage comprising top and side walls of suitable wire or fabric, the front end of the cage being open. Suitable wings 60 18 are arranged at the open end of the cage and diverge outwardly to form an enlarged entrance to the cage. The roof of the cage preferably slopes upwardly as it approaches the rear, and at the rear of the cage suitable 65 mats are provided into which the balls are driven. A mat 19 of relatively narrow width, as approximately one third of the width of the cage, is arranged centrally of the cage 70 and is secured adjacent the top of the cage.

Spaced behind the mat 19 is a mat 20 which 75 extends the entire width of the cage and from the front of the cage is visible at both sides of the central mat 19. A platform 21 is arranged beneath the mats or curtains 19 and 20 and is spaced from the ground, as shown in Figures 1 and 3. Suitable openings 22 are arranged in the platform 21 and receive cables 23 which are secured to the lower ends of the mats 19 and 20 and hang through the 80 openings 22 and extend below the platform 21. A washer or other projection 24 is secured to the lower end of each of the cables 23, and a coil spring 25 is arranged about each of the cables and rests upon the washer 24. 85 A contact washer 26 is slidably arranged on the cable and rests upon the top of the spring. A contact plate 27 is secured to the underside of the platform 21 and is provided with openings which register with the openings 22 in the platform. In normal position the contact washer 26 is spaced below the plate 27. When a ball strikes the mat, it is bulged rearwardly, the cable is drawn upward, and the washer 26 contacts with the plate 27.

Further upward movement of the cable compresses the spring 25 and presses the washer against the plate 27 to insure a good contact. The spring 25 then returns the cable to its normal position. The cables may be arranged at suitable 90 95 100

spaced points on the lower end of the mats to insure operation of the contact mechanism wherever the mat is struck by a ball.

An inclined wall of fabric or the like 28 extends from a point adjacent the platform 21 to the ground and will guide any very low balls into the mats.

The mats 19 and 20 are painted to resemble a golf course, the objects being painted in perspective. The forward, central mat 19 is painted to represent the fairway, as shown in Figure 3, and a green is painted near the top of the mat, in perspective. The portions of the rear mat 20 at the sides of the mat 19 are painted to represent the rough.

18 A driving tee is arranged at a point in front of the entrance to the cage 17 centrally thereof and comprises a bristle mat or the like 29 supported on a suitable platform 30. A transverse slot 31 extends through the mat 29 and platform 30 and an insulating strip 32 is secured in this slot. Openings 33 are arranged in spaced relation along the strip 32, and contact strips 34 are secured above and below the insulating strip. Openings 35 in the contact strips 34 register with the openings 33 and are adapted to receive the stud 36 of tees 37, a number of which extend upwardly from the slot 31. The tees 37 are preferably formed of rubber and are enlarged at their upper ends to receive the golf balls. Their lower ends are provided with openings to receive the reduced ends of the studs 36 and rings 38 may compress the tees about the studs, as shown in Figure 7. Spaced contact washers 39 are carried by the studs 36 and the upper washer normally rests upon the upper contact strip 34 while the lower washer is normally spaced below the lower contact strip as shown in Figures 6 and 7. The stud 36 extends freely through the openings in the insulating strip and contact strip but the insulating strip prevents contact of the stud with the contact strips.

45 When the tee is tilted however, as when the ball is struck, the washers 39 contact with both strips 34 as shown in Figure 14.

An object of my invention is to calculate the length of flight of the ball by timing the flight from the tee to the mat. To accomplish this I provide an indicator having suitable legs which are inserted in the ground at a point adjacent the driving tee and to one side thereof as shown in Figures 1 and 2. The indicator comprises an elongated vertical panel 40 having a central vertical slot 41 extending from a point adjacent the top of the panel to a point adjacent its center. A guide rod 42 is supported in spaced relation to the rear of the panel 40 by means of suitable brackets 43 arranged adjacent the extremities of the panel. A bracket 44 is secured adjacent the lower end of the slot 41. A slide member comprises a rod or bar 45 attached at its upper end to a horizontal cross-

piece 46 which extends through the slot 41 and is provided at its forward end with a pointer 47. A suitable knob 48 is secured to the pointer for raising it by hand. The crosspiece 36 has an opening which slidably receives the guide rod 42 and a coil spring 49 is arranged on the guide rod between the upper bracket 43 and the crosspiece 46, and when the pointer is raised to its upper position the spring 49 is compressed, as seen in Figures 10 and 11.

The lower end of the bar 45 extends through an opening in the bracket 44 and its lower end is provided with a horizontal vane 50 which is also slidably arranged on the guide rod 42. The vane 50 is for the purpose of retarding the downward motion of the pointer and the spring 43 is for the purpose of accelerating such motion, the two combining to produce a substantially constant downward or falling speed in contrast to the constant acceleration of a freely falling body. The vane is held back by the air which it displaces in its downward movement. It is obvious, however, that speed of the falling pointer may be retarded by frictional means in place of the vane.

The highest position of the pointer is marked by "zero". At a point spaced below the zero position, the scale starts with the highest yardage, here given as 300 yds., and the yardage scale decreases as the scale approaches the lower end of the slot 41. The ball is timed from the tee to the mat by the pointer. When the ball leaves the tee the indicator is released and when it strikes the mat the indicator is stopped. It will be seen that as the pointer is falling from the high yardage to the low yardage, the longer the time interval between the ball leaving the tee and striking one of the mats, the shorter will be the drive indicated in yards on the scale, and the shorter the time interval the longer the drive indicated.

Because of the spring 45 and vane 50 the scale may have substantially uniform divisions, whereas if the pointer were allowed to fall freely, the scale would have an undesirable distorted appearance.

Any suitable mechanism may be employed for releasing and stopping the pointer. In Figures 13, 14, 15 and 16 I have shown one manner of accomplishing this result. A latch 51 is pivoted to the upper bracket 43 and when the pointer is raised to zero position a stud 52 on the crosspiece 46 is engaged by the latch and the pointer is securely held in position. The latch 51 is provided with a laterally projecting arm 53 which serves as the armature for an electro-magnet 54 secured to the upper bracket 43. The coil of this magnet is wired to the contact strips 34 and a battery or other source of current supply 55 is included in this wiring. As the plates 34 are insulated from each other, the

magnet is normally de-energized. When, however, the ball is struck by a club, the tee is tilted and contact is made between the strips 34 as shown in Figure 14, thereby energizing the magnet 54, attracting the armature 53 and disengaging the latch 51 from the stud 52, allowing the spring 43 to start the pointer on its downward path.

In order to stop the falling pointer, I provide, on the bracket 44, a suitable braking device operated by the ball striking one of the mats. The braking device comprises a pair of cams 56 pivoted to the bracket 44 on opposite sides of the bar 45 and in alignment therewith. The cams are provided with toothed segments 57 which are secured to the rear faces of the cams and mesh with one another at the rear of the bar 45 as seen in Figures 15 and 16. Movement of one of the cams therefore, causes a corresponding movement of the other cam.

One of the cams is provided with a depending lug 58 to which a coil spring 59 is secured, the other end of the spring being secured to the bracket 44. As the lug 58 is arranged below the pivot point of the cam, the spring 59 tends to move the cams downwardly into engagement with the bar 45. This movement of the cams, however, is normally prevented by a pivoted latch 60 which engages a projection 61 on one of the segments. The latch 60 is extended beyond its pivot point, and this projection 62 serves as the armature for an electro-magnet 63 mounted on the bracket 44.

The coil of the magnet 63 is wired to the contact plate 27 and the contact washer 26, a battery or other source of current supply 64 being arranged in the circuit. When the ball strikes one of the mats, the circuit is closed to the magnet 63 which draws down the armature 62 thereby disengaging the latch 60 and allowing the spring 59 to pull the cams into locking position, clamping the bar 45 and preventing further movement thereof. When the pointer is raised to its upper or zero position, the cams are raised by means of a stud 65 on the bar 45 which engages one of the cams and moves it upwardly against the tension of the spring 59. As the cams are raised the projection 61 is engaged by the latch 60 which holds the cams out of engagement with the bar 45 until the magnet 63 is again energized.

While I have shown the washer 26 and plate 27 wired to the magnet 63, I contemplate substituting a pair of plates for the plate 27, one on each side of the cable 23 and wired as the plates 34 in Figure 13. Contact would then be made between the plates by the washer 26. It will also be understood that in place of the arrangement shown in Figures 13 and 14, for releasing the pointer, I may wire the lower plate 34 and the lower tee washer 39, to the coil of the magnet 54, as in Figure 15, and have the circuit to the mag-

net closed by direct contact of the lower washer with the lower plate.

After the balls strike the mats 19 and 20 they drop into an inclined trough 66 extending across the cage below the mats, and roll into the gutter 67 which carries the balls to a point adjacent the driving tee.

As there are a number of the tees 37 arranged in the slot 31 of the driving mat 29, a number of balls may be teed up at one time 75 and driven into the mats 19 and 20 which represent the golf course. When the ball is struck the pointer starts to fall and when the ball strikes one of the mats the pointer is stopped and shows, on the scale, the length 80 of the drive. After each drive the pointer must be reset by raising the knob 48 to its upper position. It will be seen, therefore, that the length of the drive is calculated by the initial velocity of the ball as shown by 85 the time interval required for the ball to pass from the tee to the mat.

It is desirable to distinguish between a straight drive which strikes the mat 19 representing the fairway, and an "off line" drive 90 which strikes the mat 20 representing the rough. This may be accomplished by adding a "bonus" to the length of a drive which strikes the mat 19. The mat 19 may be arranged closer to the tee than the mat 20; it 95 may be made of lighter material, or the washer 26 may be located nearer to the plate 27 on the mat 19, thereby stopping the pointer sooner and registering a longer drive.

While I have shown and described the preferred embodiment of my invention, it is to be understood that various changes in the size, shape and arrangement of parts may be resorted to without departing from the spirit of my invention or the scope of the subjoined 105 claims.

Having thus described my invention, what I claim and desire to protect by Letters Patent is:

1. In a golf ball driving device, a driving tee from which a ball is to be driven, a target spaced from said tee, an indicator, means operated by a ball being driven from said tee to start the operation of the indicator, and means operated by the ball striking the target to stop the operation of said indicator.

2. In a golf ball driving device, a tee from which a ball is adapted to be driven, a target spaced from said tee, an indicator having a scale and a movable pointer, means operated by the driving of a ball from the tee to start the pointer moving along the scale, and means operated by the ball striking the target to stop the movement of said pointer.

3. An indicator comprising a movable pointer, a latch to hold said pointer in inoperative position, an electro-magnet arranged adjacent said latch and adapted when energized to disengage said latch from said pointer, a braking device adapted to stop 130

the movement of said pointer, a latch adapted to engage said braking device and hold it in inoperative position, and an electro-magnet arranged adjacent said brake latch and adapted when energized to disengage said brake latch.

4. An indicator comprising a guide, an indicating member slidable on said guide, a latch adapted to engage said indicator in its inoperative position, an electro-magnet arranged adjacent the latch and adapted when energized to disengage said latch from the indicating member, means to propel the indicating member along the guide, a braking member arranged adjacent a portion of the indicating member, a latch normally engaging said braking member to hold it in inoperative position, an electro-magnet arranged adjacent said latch and adapted when energized to disengage the latch from said braking member, and means operated by resetting of the indicating member to engage the indicating member and braking member with their respective latches.

5. An indicator comprising a panel having a vertical slot therein, a guide member supported on said panel and arranged in parallel relation with the slot, an indicating pointer movable on said guide and extending through said slot, a latch pivoted adjacent the upper end of said slot and adapted to normally engage said pointer to hold it in its inoperative position, an electro-magnet arranged adjacent said latch and adapted when energized to withdraw the latch from engagement with the pointer, a spring adapted to engage the pointer under tension when the pointer is engaged by the latch, a braking cam adapted to engage a portion of said pointer, a latch engaging said braking cam and normally holding it out of engagement with the pointer, an electro-magnet arranged adjacent a portion of said latch and adapted when energized to disengage the latch from the braking member, and means to retard the acceleration of the pointer when released and propelled along the slot by the spring.

6. A golf ball driving device comprising a tee from which a ball is adapted to be driven, a target spaced from the tee, an indicator comprising a vertically falling pointer, a latch holding the pointer in its upper position, a braking device adapted to engage a portion of the pointer, a latch holding said braking device in its inoperative position, an electro-magnet adapted when energized to withdraw the first named latch from engagement with the pointer, means operated by the driving of a ball from the tee to energize said magnet and release the pointer, a second electro-magnet adapted when energized to withdraw the latch from engagement with the braking device and allowing the brake to engage the pointer, and means

operated by the ball striking the target to energize the last named electro-magnet.

7. In a golf ball driving device, a tee from which a ball is adapted to be driven, a pair of targets, an indicator having a movable pointer, means to start said pointer moving when the ball is driven from said tee, means to stop said pointer when the ball strikes one of the targets, and means to stop the pointer when the ball strikes the other target, the pointer being stopped in a smaller interval of time when one target is struck than when the other target is struck.

8. In a golf driving device, an insulating member having an opening therein, a contact plate arranged above said member adjacent said opening, a second contact plate arranged below said insulating member adjacent the opening therein, a tee freely and tiltably disposed in said opening in the insulating member and having a contact member resting upon the upper contact plate, and said tee having a lower contact member disposed below and normally spaced from the lower contact plate, whereby when a ball is driven from said tee it will be tilted and both contact members will engage the contact plates on the insulating member.

9. In a golf driving device, an insulating member having an opening therein, a pair of contact plates secured to said member one on each side thereof, and having openings therein registering with the opening in the insulating member, a tee having a stud extending through the openings in the plates and insulating member, and having a substantially smaller diameter than said openings, a contact washer secured to the stud and normally resting on the upper contact plate, and a lower contact washer arranged on said stud and normally disposed below and spaced from the lower contact plate, whereby when a ball is driven from said tee the tee will tilt and the contact washers will engage both of the contact plates.

10. In a golf ball driving device, a driving tee from which a ball is to be driven, a target spaced from said tee, an indicator, electrical apparatus connecting the teeth with the indicator to start the operation of the indicator when a ball is driven from the tee, and electric apparatus connecting the target with the indicator and operated by the ball striking the target to stop the operation of the indicator.

11. In a golf ball driving device, a tee from which a ball is adapted to be driven, a target spaced from said tee, an indicator having a scale and a movable pointer, electrical apparatus connected to the tee and operated by the driving of a ball from the tee to start the pointer moving along the scale, and electrical apparatus connected to the target and operated by the ball striking the target to stop the movement of the pointer.

12. In a golf ball driving device, a driving tee from which a ball is adapted to be driven, a target spaced from said tee, and a timing apparatus to time the flight of the ball from tee to target, said timing apparatus being operatively connected with the tee and the target and being set in operation by driving a ball from the tee and being stopped by the contact of the ball with the target.
13. In a golf ball driving device, a tee from which a ball is to be driven, a target spaced from said tee, a time operated apparatus, and electrical connections between said tee and time operated apparatus and between said target and time operated apparatus to set the time operated apparatus in operation when the ball is driven from the tee and to stop the operation of the time operated apparatus when the ball reaches the target.
14. In a golf ball driving device, a tee from which a ball is to be driven, and means operatively connected to said tee and to a point spaced from said tee to determine the approximate distance a ball driven from said tee would travel if uninterrupted in its flight, by automatically timing the flight of the ball from the tee to the said point spaced from said tee.
15. In a golf ball driving device, a tee from which a ball is to be driven, and means operatively connected to said tee and to a point spaced from said tee to translate the time interval required by the flight of the ball from the tee to said point spaced from the tee into the approximate distance the driven ball would travel if uninterrupted in its flight.
16. In a golf ball driving device, a driving tee from which a ball is to be driven, a target spaced from said tee, and means operatively connected to the tee and target and operated by driving a ball from the tee to the target to determine the approximate distance of the flight of the ball from the time interval required by the ball to travel from tee to target.
17. In a golf ball driving device, a driving tee from which the ball is adapted to be driven, a target spaced from said tee, and means operatively connected to the tee and target and operated by driving a ball from the tee to the target to time the flight of the ball from the tee to the target, and means to translate the time interval of the flight of the ball from tee to target into the distance the ball would have traveled if it had not been stopped by the target.

In testimony whereof I affix my signature.
BLANCHARD D. SMITH.
